(57) **CLAIM**

We claim, the ornamental design for a laser measurement device, as shown and described.

DESCRIPTION

FIG. 1 is a perspective view of a first embodiment of the invention;
FIG. 2 is a front plan view of the embodiment of FIG. 1;
FIG. 3 is a rear plan view of the embodiment of FIG. 1;
FIG. 4 is a first side plan view of the embodiment of FIG. 1;
FIG. 5 is a second side plan view of the embodiment of FIG. 1;
FIG. 6 is a top plan view of the embodiment of FIG. 1;
FIG. 7 is a bottom plan view of the embodiment of FIG. 1;
FIG. 8 is a perspective view of a second embodiment of the invention;

FIG. 9 is a front plan view of the embodiment of FIG. 8;
FIG. 10 is a rear plan view of the embodiment of FIG. 8;
FIG. 11 is a first side plan view of the embodiment of FIG. 8;
FIG. 12 is a second side plan view of the embodiment of FIG. 8;
FIG. 13 is a top plan view of the embodiment of FIG. 8;
FIG. 14 is a bottom plan view of the embodiment of FIG. 8;
FIG. 15 is a perspective view of a third embodiment of the invention;
FIG. 16 is a front plan view of the embodiment of FIG. 15, the rear plan view being the same as FIG. 10;
FIG. 17 is a first side plan view of the embodiment of FIG. 15;
FIG. 18 is a second side plan view of the embodiment of FIG. 15;
FIG. 19 is a bottom plan view of the embodiment of FIG. 15, the top plan view being the same as FIG. 13;
FIG. 20 is a perspective view of a fourth embodiment of the invention;
FIG. 21 is a front plan view of the embodiment of FIG. 20, the rear plan view being the same as FIG. 10;
FIG. 22 is a first side plan view of the embodiment of FIG. 20;
FIG. 23 is a second side plan view of the embodiment of FIG. 20;
FIG. 24 is a bottom plan view of the embodiment of FIG. 20, the top plan view being the same as FIG. 13;
FIG. 25 is a perspective view of a fifth embodiment of the invention;
FIG. 26 is a front plan view of the embodiment of FIG. 25;
FIG. 27 is a rear plan view of the embodiment of FIG. 25;
FIG. 28 is a first side plan view of the embodiment of FIG. 25;
FIG. 29 is a second side plan view of the embodiment of FIG. 25; and,
FIG. 30 is a top plan view of the embodiment of FIG. 25, the bottom plan view being the same as FIG. 24.
The phantom lines shown in FIG. 1-FIG. 30 are environmental and not part of the claimed design.
The color and shading shown in FIG. 1-FIG. 30 forms no part of the claimed design, the laser measurement device according to the claimed design may be any color or combination of colors.
The surface treatment shown in FIG. 1-FIG. 30 forms no part of the claimed design, the laser measurement device of the claimed design may have any surface treatment.
References to “side”, “top”, “front”, “rear” and “bottom” in the figure descriptions are not meant to require certain in-use orientation; a laser measurement device according to the claimed design may be used in any orientation.
